B. AMES.
PACKAGE OF RAZOR PARTS.
APPLICATION FILED MAR. 27, 1919.

Patented Feb. 10, 1920.

UNITED STATES PATENT OFFICE.

BUTLER AMES, OF LOWELL, MASSACHUSETTS.

PACKAGE OF RAZOR PARTS.

1,330,297.

Specification of Letters Patent. Patented Feb. 10, 1920.

Application filed March 27, 1919. Serial No. 285,437.

To all whom it may concern:

Be it known that I, BUTLER AMES, a citizen of the United States, and resident of Lowell, in the county of Middlesex and State of Massachusetts, have invented new and useful Improvements in Packages of Razor Parts, of which the following is a specification.

This invention relates to packages of 10 razor parts and more particularly to an assemblage of razor parts comprising a box or casing in which is contained the disassembled parts of a magnetic safety razor, *i. e.* a razor comprising essentially a magnet and associate parts of paramagnetic material such, for example, as that shown in Reissue Letters Patent of the United States, No. 14,551, granted to me on November 19, 1918.

As is well known, safety razors are largely used by soldiers, campers, travelers and other persons who are forced of necessity to rigid economy of space in their packs or baggage and who find it difficult and often impossible to carry articles or packages having sharp corners, or otherwise of awkward shape even though such articles or packages are relatively small. It is, therefore, a great desideratum that the razor when not in use shall be packed in light, small and very compact compass, and also that the package be without corners which render its packing difficult and often impossible, and prevent it from being readily carried in the pocket of the user when emergency so requires.

It is the principal object of this invention to provide for the package of disassembled razor parts in small, light and very compact compass, in such shape as to facilitate packing or carriage on the person under any and all conditions of service. It is a further object of the invention to provide in the package as part thereof, a blade package adapted to facilitate the compact packing of a plurality of blades and to protect their cutting edge or edges until such time as they are successively removed for use.

Referring to the drawings which illustrate an embodiment of my invention,—

Figure 1 is a sectional view of my improved package of razor parts;

Fig. 2 is a transverse sectional view of

the package taken on a plane near the top of Fig. 1, the cover being removed.

55

Fig. 3 is a perspective view of a blade holder;

Fig. 4 is a similar view of the cover of said holder;

Fig. 5 is a perspective view of my improved blade package;

Figs. 6, 7 and 8 are plan views of razor blades;

Fig. 9 is a plan view of a paper covering for blades; and

65

Fig. 10 is a perspective view of the complete package of razor parts.

A is a box or casing, preferably of metal and provided with a cover A¹. Said casing is U-shaped in cross-section to conform to 70 the contour of the U-magnet B, which forms the razor handle, and which is adapted snugly to fit into said casing and when fitted therein is held against lateral movement by the wall of said casing.

75

Said guard member as clearly shown in Fig. 2 overlaps the legs of the magnet and the cap member D preferably abuts against the wall of the casing. The cap member is made of paramagnetic material and the guard member may or may not be paramagnetic. The parts may be placed in the casing A as shown in such a manner that the cap D is also mechanically wedged against the guard C by the wall of the casing and 85 in that case the holding effect of the magnet is exerted only to prevent endwise slippage of the parts.

Disposed upon the opposite side of said magnet B is an improved supply of blades, 90 preferably assembled in the form shown (Figs. 3 to 5) consisting of a metal base E (Fig. 3) of any suitable paramagnetic material, provided with a pair of upwardly extending tenons or blade holders F spaced 95 apart, preferably formed integral with said base and folded or turned over at f to hold a plurality of blades G. Preferably a cover member H (Fig. 4), of the same material as

said base, rests upon the uppermost blade 100 of the package and the free ends of said holders F overlap the cover member removably to secure the blades as clearly shown in Fig. 5. The tenons or holders F may be either flexible or resilient; or, preferably, both, so that the tenons F may be

105

sprung toward each other to release the cover H and one of the blades; or when the package of blades is of lesser number, may be bent permanently nearer the base E than the points f.

It will be observed that the base E and cover F are of greater area than the blades and project beyond them, thus protecting the cutting edge or edges of the blades until they are successively removed from the package for service.

The particular form of the aperture which permits the blades G to be threaded onto the holders F is not material. It may be an elongate slot, as shown in Fig. 6, or a pair of spaced openings, as shown in Fig. 7, or a pair of marginal recesses, as shown in Fig. 8, or any other suitable constriction. If desired, the cover member H may be dispensed with and the holders F turned over upon the topmost blade to secure the package; also, if desired, the individual blades may be provided with a paper covering or envelop J (Fig. 9) provided with apertures 25 K to permit the blades to be threaded onto the holders.

The blade package or holder above described and shown in Fig. 5 is disposed in the casing A at the side of the magnet B as shown in Fig. 2. Its base E and cover F are of sufficient width not to pass freely between the legs of the magnet B and as said base and cover are of paramagnetic material, whichever of these two parts happens to be toward the magnet upon insertion of the package into the casing, is drawn thereto and held thereby so that the package is held against movement in the casing under all shocks or jars usually incident to transportation.

The package or assembly of razor parts above described is very small, light and compact. All partitions or the like within the casing usually employed to separate and hold the various parts against rattling are eliminated, and at the same time, effective provision is made for preventing any movement of the parts within the casing. Furthermore, the package is without corners and thus of a shape which permits it to be readily packed under any and all conditions of service; and, if necessary or desirable, it can be readily carried in the pocket of the user without the slightest inconvenience. 55 The improved blade holder or package is adapted to coöperate with the other parts to form a compact package, and, moreover,

provides efficient means for storing a relatively large number of blades and keeping them in condition for service as they are required.

I claim:

1. A package of disassembled razor parts comprising a casing, a magnet in said casing removably held against lateral movement by the wall thereof, and paramagnetic parts held by said magnet. 65

2. A package of disassembled razor parts comprising a casing, a magnet in said casing removably held against lateral movement by the wall thereof and paramagnetic parts disposed at the side of said magnet and held thereby. 70

3. A package of disassembled razor parts comprising a casing, a U-magnet in said casing, said casing conforming to the contour of said magnet whereby said magnet is removably held against lateral movement in said casing, and paramagnetic parts disposed at the side of said magnet and held 80 thereby. 75

4. A package of disassembled razor parts comprising a casing, a magnet in said casing removably held against lateral movement by the wall thereof, and a blade package disposed at the side of said magnet within 85 said casing and held thereby.

5. A package of disassembled razor parts comprising a casing, a magnet in said casing removably held against lateral movement by the wall thereof, and a blade package disposed at the side of said magnet and held thereby, said blade package comprising a base having a pair of spaced blade holders, said holders adapted to be passed 95 through an apertured razor blade and thereafter to be turned over removably to hold said blade. 90

6. A package of disassembled razor parts comprising a casing, a U-magnet in said casing, said casing conforming to the contour of said magnet whereby said magnet is removably held against lateral movement in said casing, a blade package of paramagnetic material disposed at one side of said 105 magnet and held thereby and a guard and cap fitted together disposed on the opposite side of said magnet, said guard abutting against said magnet and said cap abutting against the wall of said casing. 110

Signed by me at Lowell, Massachusetts, this twenty-second day of March 1919.

BUTLER AMES.
